UNITED STATES PATENT OFFICE.

JAMES R. JACKSON, OF OAKLAND, CALIFORNIA, ASSIGNOR OF ONE-HALF TO ROY MAUVAIS, OF SAN FRANCISCO, CALIFORNIA.

SCALE-POISE.

1,307,818.

Specification of Letters Patent. Patented June 24, 1919.

Application filed June 2, 1917, Serial No. 172,415. Renewed November 8, 1918. Serial No. 261,714.

To all whom it may concern:

Be it known that I, JAMES R. JACKSON, a citizen of the United States, residing at Oakland, in the county of Alameda and State of California, have invented new and useful Improvements in Scale-Poises, of which the following is a specification.

This invention relates to a scale poise.

One of the objects of the present invention is to provide a simple, substantial, cheaply manufactured poise and balance ball for scale beams, which are more sensitive in action and which are adapted to be locked to the beam when adjusted, thereby preventing employees or unauthorized persons from tampering with the scale or putting it out of adjustment accidentally, maliciously, or otherwise. Further objects will hereinafter appear.

20 The invention consists of the parts and the construction and combination of parts as hereinafter more fully described and claimed, having reference to the accompanying drawings, in which—

25 Figure 1 is a perspective view of the beam on the scale, showing the application of the invention.

Fig. 2 is an end view of the poise and the beam.

30 Fig. 3 is a central, longitudinal section through the poise and beam, showing the application of the key-actuated locking mechanism.

Fig. 4 is a longitudinal section through the balance ball, showing the application of the locking mechanism.

Fig. 5 is a cross section on line 5—5 of Fig. 4.

Referring to the drawings in detail, A indicates the beam, having the usual sliding poise, of a standard form of scale, 2 the knife bearing rest on which the beam is supported, 3 the pillar, 4 the steelyard rod and loop, 5 the beam rack, 6 the poise and 7 the balance ball. The construction of the poise 6 and the balance ball 7 forms the main subject-matter of the present invention and will be as follows:

Referring to Figs. 2 and 3, it will be seen 50 that the greater body portion of the weight or poise is positioned above the beam, as indicated at 8, while the lower portion 9 merely forms a guide to support it upon the beam. The location of the weight above the beam is of considerable importance for the

reason that it renders the beam more sensitive and active than is otherwise the case. The lock employed in this instance is a standard type of "Yale" lock and consists of a housing 10 which is suitably secured in 60 the end of the beam A. Mounted interiorly of the housing 10 is a barrel 11 adapted to receive the key in the usual manner.

The inner end of the barrel extends through the casing of the lock and has secured thereon a cam member 12, which is adapted to be moved into and out of register with notches 13 formed in the sides of the poise. The notches are preferably V-shaped and the face of the cam is similarly 70 shaped to take up wear and also to reduce any tendency of play when in interlocking position. The poise, when once applied and locked in position, cannot, therefore, be moved, displaced or tampered with as it is 75 first necessary to insert a key and turn the barrel to a position where the cam is out of engagement with the notches 13 before the poise can be removed.

The locking mechanism employed in connection with the balance ball 7 consists of the following parts: Mounted interiorly of the ball, in a recess formed therefor, is a clamping block 14. This block is set into the recess when ball is threaded and the 85 threads formed therein will, therefore, coincide or form a continuation of the threads extending from end to end of the ball. Formed exteriorly of the ball is an annular groove 15, in which is turnably mounted a 90 ring 16. This ring is provided with a recess for the reception of a spring-actuated locking pin 17 and is also provided with an opening 18 which is adapted to be turned into and out of register with a set-screw 19, 95 which is provided for the purpose of releasing or moving the clamping block into engagement with the threaded rod extension 20 of the beam.

Formed in one end of the balance ball 100 proper is a slot or opening 21, which is formed for the reception of a key 22 and also for the reception of the locking pin 17. The forward end of the key employed is wedged-shaped, as at 23, and as the inner 105 end of the locking pin is also wedge-shaped, as shown at 24, it can readily be seen that the insertion of the key will force the pin out of engagement with the slot 21, thereby permitting the ring 16 to be turned until 110

the opening comes into register with the set-screw 19. This may then be released by means of a screw driver and the poise as a whole may be turned upon the threads of the rod 20 until a proper adjustment has been made. The screw is then reset to lock the poise or to force the clamp 14 into engagement with the threads.

The key may then be removed and the ring 16 turned in the annular groove until the locking pin snaps into the slot 21. The ring will in this manner become locked against turning movement and as the set-screw has already been set and the opening 18 has been moved to a position out of alignment with the set-screw, it is obvious that it will be impossible to turn the ball as the ring 16 covers the screw, thereby preventing any person from releasing it; in other words, both the poise and the balance ball are locked by means of a key and it, therefore, requires possession of the key to remove the poise or re-adjust the balance ball. Unbalancing of the scale accidentally, maliciously, or otherwise is in this manner prevented and a more sensitive and active beam action is permitted, as the major portion of the weight contained in the poise 6 is positioned above the beam.

30 While two forms of blocks are here shown, it is obvious that I do not wish to limit myself to either specific structure shown as practically any form of key-actuated lock might be employed. Also, I wish it understood that the materials and finish of the several parts of the device may be such as the experience and judgment of the manufacturer may dictate.

Having thus described my invention, what 40 I claim and desire to secure by Letters Patent is—

1. The combination with a scale beam, of

Copies of this patent may be obtained for five cents each, by addressing the "Commissioner of Patents, Washington, D. C."

a poise mounted on the end of the beam, and having notches formed therein a cam member carried by the beam, and a key-actuated 45 lock adapted to turn the cam into and out of register with said notches formed in the poise.

2. In combination with a scale beam, a poise mounted thereon, a key actuated lock 50 having a movable barrel carried by one of said two first named elements, and interengaging means between the barrel and one of said two first named elements for locking the poise to the beam.

3. In combination with a scale beam, having an opening extending through an end thereof, a key actuated lock mounted in said opening so as to enable the key to enter the lock from said end of the beam, a poise 60 on the beam, and means operable by the lock movements for locking the poise to the beam.

4. In combination with a scale beam, a poise mounted thereon, a key actuated lock 65 borne by one of said elements, and interengaging means between the lock and one of the two said first named elements for locking the poise on the beam.

5. In combination with a scale beam, a 70 poise mounted thereon and formed with a weighted enlarged head at its upper end located above the beam and having a lower part for supporting the poise on the beam, and means co-operating with the lower part 75 of the poise to lock the latter to the beam.

In testimony whereof I have hereunto set my hand in the presence of two subscribing witnesses.

JAMES R. JACKSON.
